UNITED STATES PATENT OFFICE.

TOMAS MOCYDLARZ, OF STRATHCONA, ALBERTA, CANADA.

ENVELOP-MOISTENING DEVICE.

1,077,201.

Specification of Letters Patent.

Patented Oct. 28, 1913.

Application filed April 15, 1913. Serial No. 761,334.

To all whom it may concern:

Be it known that I, TOMAS MOCYDLARZ, a subject of the Emperor of Germany, residing at Strathcona, Alberta, Canada, have 5 invented certain new and useful Improvements in Envelop-Moistening Devices, of which the following is a specification, reference being had therein to the accompanying drawing.

10 This invention relates to an envelop moistening device and the primary object of my invention is to provide a simple, inexpensive and durable device that can be advantageously used in large mercantile 15 houses for expeditiously moistening a large number of envelopes, thereby obviating the necessity of using the tongue or a sponge for such purposes.

20 A further object of this invention is to provide a moistening device in the form of a spherical receptacle that has a novel moistening head and a yieldable base whereby the receptacle can be supported upon a desk without any danger of the same upsetting 25 or tilting.

I attain the above objects by a mechanical construction that will be hereinafter specifically described and then claimed, and reference will now be had to the drawing, 30 wherein:—

Figure 1 is a vertical sectional view of a moistening device in accordance with this invention, Fig. 2 is a top plan of the same, and Fig. 3 is a bottom plan of the device.

35 A device in accordance with this invention comprises a hollow spherical receptacle 1 that has the bottom thereof provided with a plurality of flat resilient legs or springs 2 that are connected by screws 3 or other 40 fastening means to a circular base 4. The top of the base 4 is concave, as at 5 to provide clearance for the bottom of the receptacle. The top of the receptacle has an opening 6 in communication with a neck 7 45 that is exteriorly screw threaded, as at 8. The neck 7 has an annular supporting flange 9 and resting upon said supporting flange is a moistening head, comprising a piece of absorbent material 10 inclosed by a casing 11.

Felt, a piece of sponge or other absorbent 50 can be used and incased by a piece of fabric or other pervious material. The moistening head is retained upon the shoulder 9 by a cap 12 screwed upon the neck 7 and an opening 13 in said cap allows a portion or reduced 55 end of the moistening head to protrude from the cap whereby said head can be used for the purposes for which it is intended.

The breast or top of the receptacle 1 has 60 a filling opening 14 normally closed by a screw plug 15, said opening permitting of mucilage, liquid paste or water 16 being placed within the receptacle.

After the moistening head has been used 65 for moistening or applying mucilage to the flap of an envelop the device can be inverted and the base 4 used for sealing purposes.

What I claim is:—

1. An envelop moistening device comprising a hollow spherical receptacle having an opening in the top thereof, an annular neck integral with the periphery of the receptacle at the top thereof and provided with an inwardly extending annular flange flush with 75 the wall of said opening to provide a support, a casing supported by said flange and having an inset outer portion projecting above said neck, an absorbent body mounted in said casing and supported by said flange, 80 a flanged cap secured to the neck and overlapping the casing for maintaining it in position, and a filling opening provided for said receptacle.

2. An envelop moistening device comprising 85 a hollow spherical receptacle having an opening in the top thereof, an annular neck integral with the periphery of the receptacle at the top thereof and provided with an inwardly extending annular flange flush 90 with the wall of said opening to provide a support, a casing supported by said flange and having an inset outer portion projecting above said neck, an absorbent body mounted in said casing and supported by 95 said flange, a flanged cap secured to the neck and overlapping the casing for maintaining it in position, a filling opening provided for

said receptacle, and means for resiliently supporting said receptacle.

3. An envelop moistening device comprising means to provide a water reservoir, a moistening element connected with said means and adapted to receive the water therefrom, and means for resiliently supporting said receptacle whereby the same

can be vertically moved to agitate the water to supply the latter to said element. 10

In testimony whereof I affix my signature in the presence of two witnesses.

TOMAS MOCYDLARZ.
